Primary Examiner — Doris Clark(74) *Attorney, Agent, or Firm* — Workman Nydegger(57) **CLAIM**

The ornamental design for a panel for polygonal partitions, as shown and described.

DESCRIPTION

FIG. 1 is a top, right, front perspective view of our new design for a panel for polygonal partitions shown in a configuration of use;

FIG. 2 is a top, left, front perspective view of the panel for polygonal partitions;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The surface lines shown in the Figures denote surfaces of materials that are transparent or semi-transparent.

The broken line showing of elements on the panel for polygonal partitions illustrate portions of the article and form no part of the claimed design.
